UNITED STATES PATENT OFFICE.

EDWARD G. PARKHURST, OF HARTFORD, CONNECTICUT, ASSIGNOR TO HIMSELF AND THE PRATT & WHITNEY COMPANY, OF SAME PLACE.

MACHINE-GUN.

SPECIFICATION forming part of Letters Patent No. 228,777, dated June 15, 1880.

Application filed January 22, 1880. Patented in England May 30, 1879.

To all whom it may concern:

Be it known that I, EDWARD G. PARKHURST, of Hartford, in the county of Hartford and State of Connecticut, have invented certain new and useful Improvements in Machine-Guns; and I do hereby declare that the following is a full, clear, and exact description thereof, whereby a person skilled in the art can make and use the same, reference being had to the accompanying drawings, and to the letters of reference marked thereon.

Like letters in the figures indicate the same parts.

My improvements relate to machine-guns such as are usually furnished with one or more barrels and are automatically loaded and fired by a mechanism at the breech, which is operated by turning a crank so as to discharge the gun with great rapidity.

The object of my present invention is to render the gun more efficient and serviceable by providing a better and more positively-acting feeding and ejecting mechanism than has heretofore been used, and by also providing an improved lock mechanism, the firing devices of which can be thrown in or out of action, as desired.

My invention consists in the construction and arrangement of the several parts, as will be hereinafter described.

In the accompanying drawings, on three sheets, Figure 1 is a longitudinal vertical section through the breech mechanism and part of one of the barrels of a gun embodying my improvements and showing the working parts of the breech mechanism. Fig. 2 is a horizontal section through the breech and part of the barrels, showing a full top view of the breech mechanism. Fig. 3 is a side sectional view of one of the locks detached, also showing one of the circular cams which operate the locks. Fig. 4 is a top view of the same. Fig. 5 is a front view of the lock, as shown in Fig. 3, without the cam. Fig. 6 is a top view, upon a larger scale, of the sliding feed-plate which regulates the feeding of the cartridges into the barrels. Fig. 7 is a side view of the same. Fig. 8 is a vertical cross-section upon a larger

scale, taken through the case which contains the cartridges fed to the gun and through the feeding mechanism upon the line *xy* of Fig. 1. Fig. 9 is a bottom view of the case or box which contains the cartridges to be fed to the gun. Figs. 10, 11, and 12 are details, which will be hereinafter described. Fig. 15 shows a top and edge view of the retractor *B* detached.

A is the outside case of the breech of the gun, forming a box, within which the mechanism for loading and firing operates.

B and *B'* are the barrels, of which only a part is shown in the drawings. They may be of any ordinary length or construction, and are screwed into or otherwise attached to the front end of the case *A*.

C is the cascabel, which is constructed so as to unscrew and release the top of the case *A*, so that it can be raised to get at the interior containing the working parts.

The case *A* is hinged to the carriage at *A'*, to serve as trunnions for the gun. The carriage is constructed in the usual manner.

D is a crank, the turning of which operates the mechanism of the gun.

E and *E'* are the lock-bars, which are alternately driven forward and back by the cams *G* and *G'*. These lock-bars push the cartridges into the barrels to be fired and withdraw the empty shells, so that they drop down through the opening *H* in the case *A*. The forward ends of these lock-bars are furnished with firing-pins and mechanism for withdrawing the expended shells.

J is the bolt of the lock, the part for firing which will be hereinafter described.

K is a removable feed-box, which is placed in a socket in the case *A*, filled with cartridges, in the position shown in Fig. 1, and is replaced when exhausted. A section of it is shown in Fig. 8 and a bottom view in Fig. 9. Directly under this feed-box are openings in the case *A*, of sufficient size to admit a cartridge.

L is a reciprocating sliding feed-plate, more particularly shown in Figs. 6, 7, and 8, which moves from side to side in suitable guides in the fixed case *A*, and serves to force the suc-

sive cartridges down into the proper position to be pushed into the barrel by the lock-bar E. This sliding feed-plate is furnished with two inclined longitudinal slots, M and M', of 5 just sufficient size to pass the cartridge. The middle part of the plate is cut away so as to rest upon the abutment N, and the sides are cut away so as to slide in contact with the projections O and O'. These projections extend 10 nearly the whole length of the cartridge.

The operation of a cartridge passing through this feed-plate is as follows: In Fig. 8 of the drawings the feed-plate has passed to the left, and the row of cartridges in the right side has 15 passed down so that the bottom one rests between the projection L² and the abutment N. Now, as the feed-plate passes to the right the part L' enters between the two lower cartridges and forces the lower one down into the receptacle below, from whence it is pushed into the barrel. This lowest cartridge cannot be pushed out of position on account of the projection O', and must move downward under the influence 20 of the incline upon L'. The second cartridge 25 is caught and held upon the top of L', as shown in the left side of the figure. As the part L' arrives at the opposite end of its throw, or to the right, the bottom cartridge on the left falls down and is held between L³ and N, ready 30 to be forced down by the feed-plate at its next movement.

The feed-plate is furnished with suitable guides P in the fixed case or frame, upon which it slides. It receives its motion by means of 35 a lever, R, which is shown in the drawings as forked at its rear end, and it is thrown alternately to one side and the other by the cam-projections S and S' on the lock-bars.

When the loaded cartridge falls into the receptacle below the feed-plate ready to be pushed into the barrel, it is held there by its forward end resting upon a shelf and its rear end being supported by the enlarged rim, the opening in the bottom of the receptacle not 45 being large enough to let the rim pass through until the shell is drawn farther back than this position.

T and T' are the ejecting-levers, which serve a double purpose of holding the shell in the 50 receptacle by means of their enlarged ends I² until it is retracted sufficiently to pass through the bottom, when they strike it upon the side and expel it. This is effected by making the lower corner of the front end of the ejector at T² strike the shell a little above the middle. This forces it out of the gun with great certainty. These ejecting-levers are pivoted to the sides of the case, as shown in the drawings, Fig. 2, and are operated by the dogs E² 55 E³ upon the lock-bars E and E'. When the lock arrives at its most rearward position the dog engages the cam or projection upon the rear or shorter end of the lever and throws the front end forcibly inward to eject the shell. 60 This position is shown upon the upper side of Fig. 2. When the lock-bar moves to its most

forward position the dog strikes the forward or longer arm of the lever and throws it back to allow the lock to pass and push the shell home into the barrel.

The cartridge is deposited in its receptacle back of the barrel, while the forward end of the lever is inward, so that the cartridge cannot move to the rear. When the spent shell is drawn back by the extractor upon the lock-bar the ejector strikes it after it has passed farther to the rear than the position in which it entered, so that the enlarged rim upon the shell comes over an enlarged portion of the slot through the bottom of the case and allows the shell to fall freely out.

U is a plate, which is screwed upon the abutment N when the gun is to be used with cartridges having a reduced end smaller than the chamber of the shell, so that the ball can be 85 of smaller diameter. This plate serves to support and direct the front end of the cartridge, so that it will be in the exact position required to support the cartridge above it in a horizontal position and allow the portion L' of the 90 slide L to enter smoothly between the lower cartridge and the one next above it.

In the middle of the case K, between the two channels which contain the cartridges, are two small arms, V and V', (see Figs. 8, 9, 95 10, and 11,) which spring out and retain the cartridges as soon as the case K is lifted. These arms are hinged to a plunger, W, moving in a cylindrical hole in K, which is pressed downward by a spring, X. The arms V and 100 V' are provided with inclined slots Y and Y', through which passes the pin Z, the ends of which are set in the case or feed-box K.

When the case K is lifted up out of its socket the spring X presses down the plunger 105 W, and the arms V and V', guided by the slots, are forced outward and hold the remaining cartridges in the case. When the case is replaced the arms V V' come in contact with the bottom of its socket and shut the arms in to the position shown in Fig. 8. These arms thus act automatically whenever the case K is removed to be filled or for any other purpose.

The thumb-latch A² (shown in Figs. 1, 9 and 12) is for the purpose of holding the case 115 K in its place when in use attached to the gun. The case is removed by pressing down the latch, which releases the hook.

The lock mechanism, the details of which are more particularly shown in Figs. 3, 4, and 120 5, will now be described.

The firing-bolt J has upon its rear end the head J², and near its forward end it is provided with a fixed collar, J³. J⁴ is a sleeve sliding freely upon the bolt J. J⁵ is a spiral 125 spring acting between the sleeve J⁴ and the fixed collar J³. J⁶ is a rocking lever pivoted to the lock-bar E, the upper end of which is provided with a segmental gear working in a rack on the under side of the sleeve J⁴. J⁷ is 130 a hooked lever which catches upon the head J² when the latter is drawn to the rear by the

lever J^6 . This hook is released by the cam G acting upon the upper end of the lever.

A^3 is a fixed block, and A^4 is a sliding block for operating the lower arm of the lever J^6 .

5 The operation of these parts is as follows: In Fig. 1 the position of the lock shown in full lines is that of having just been fired. When the cam G draws back the lock-bar E the lower end of J^6 mounts upon the block A^3 , releases 10 the pressure upon the spring, and throws the bolt back, so that its head engages with the hook on the lever J^7 . The spring remains relaxed until the lock-bar has again passed forward until the end of the lever J^6 passes off 15 from the block A^3 and engages with the block A^4 . The sleeve is then thrown forward and the spring compressed. This is just before the lock-bar arrives at its extreme forward position. When the cartridge is pressed entirely 20 home the cam G releases the lever J^7 and the firing-bolt is driven forward by the spring. It will thus be seen that the cocking of the lock is done by the sliding block A^4 just before the firing.

25 A^5 is an exterior handle-crank, connecting by means of a shaft with the interior crank, A^6 , which is attached to the sliding block A^4 by the connecting-link A^7 . By means of the handle A^5 the block A^4 can be readily drawn 30 back out of reach of the lever J^6 , so that it will not operate it and cock the gun. The spring then remains relaxed, as shown in the position of the parts in Fig. 3, so that live cartridges can be run through the gun without firing, if 35 desired.

The discharging of the gun can be at any time instantly stopped by means of the handle A^5 , even while the locks are in operation and cartridges in the gun. The extracting mechanism is operated by the movement of the lock-bar E .

40 B^2 is the retractor. It consists of a bent lever having a fixed pivot in the case A at the rear end of the barrel. Its forward end forms a hook, which rests directly under the enlarged rim of the cartridge-shell, and its rear end forms an arm, which enters into a recess in the forward end of the lock-bar (shown at B^3 in Figs. 1 and 2) when the shell is pushed home 45 in the barrel. When the lock-bar is drawn to the rear the arm of the retractor lifts out of this recess and passes over the end of the lock-bar, thereby drawing the shell back a short distance and loosening it from the chamber in 50 the barrel.

55 C^2 is a spring-extractor, attached at its rear end to the lock-bar, and provided with a hook at its forward end, which hooks over the rim of the cartridge when it is pushed home in the barrel. This extractor draws back the expended shell until it is out of the barrel and is discharged by the ejector T , as has been before described. In connection with this extractor the retractor B^2 serves another purpose than that before described of withdrawing the shell from the barrel. It holds the

head of the cartridge out of the barrel until the hook on the extractor C^2 passes over the rim, so that this operation is always outside of the chamber and does not require a larger 70 recess for the hook end of the extractor than will just permit it to enter. If the cartridge is pushed home by the blow of the lock-bar striking it, it will be withdrawn again when the end of the bar reaches the arm of B^2 . The 75 end of the lock-bar will push in the arm of B^2 and allow the cartridge to hook under the extractor C^2 before the lock-bar pushes home the cartridge and the arm of B^2 enters the recess B^3 . 80

E^5 and E^6 are rollers under the rear ends of the lock-bars, to diminish the friction of their movement forward and back. The axes of these rollers project and run under guides E^7 , so that the lock-bars are held down and cannot be jarred out of their proper line of motion by the firing of the gun or from any other cause. 85

Figs. 13 and 14 show more particularly the construction of the cams which operate the 90 lock-bars to drive the cartridges into the barrels. It has been found that the cams as ordinarily constructed soon wear out, owing to the difficulty of hardening them or the lock-bars on account of their peculiar form. I 95 therefore attach a separate plate, G^2 , to the faces of the cams, as shown in Figs. 13 and 14, which obviates the difficulty. These tempered plates are attached by screws, as shown in the drawings. They extend across the face of the 100 cam and operate against the forward vertical part of the lock-bar to drive home the cartridge.

What I claim as my invention is—

1. The combination of the reciprocating feed-plate L , having inclined parts L^1 L^2 L^3 , 105 with the fixed parts or guides O O' of the feeding mechanism, whereby the cartridges in the columns above are held and successively forced downward into the receptacle beneath, substantially as herein set forth. 110

2. The ejecting-lever T , operated, as described, by a dog on the lock-bar, and arranged as described with reference to the delivery-opening, to serve as a rear stop for the cartridge, substantially as herein set forth. 115

3. The feeding-case having projecting arms V V' hinged to the plunger W and pressed down by a spring, so that the pin Z acts upon the slots Y Y' to force out the arms and stop the descent of the cartridges when the case is removed from its socket, substantially as described. 120

4. The plate U , secured to and projecting beyond the abutment N , which forms one wall of the channel through which the cartridge 125 passes from the feed-box, in combination with said abutment for supporting the reduced end of the cartridge, so that the cartridge remains in a horizontal position while passing downward, substantially as described. 130

5. The combination of the bolt J , having the head J^2 and collar J^3 , with the releasing-hook

J^7 , the sleeve J^4 , and its rack, the spring J^5 , and the lever J^6 , with its segmental gear operating to give tension to the spring after the bolt is hooked, substantially as described.

- 5 6. The combination of the fixed block A^3 and the movable block A^4 with the lever J^6 and the lock mechanism, whereby the parts of the lock are operated, substantially in the manner herein described.
- 10 7. The combination of the retractor B^2 , turning on a fixed pivot at the rear end of the bar-

rel, with a movable lock-bar, E , provided with a notch or recess, B^3 , by which said retractor is operated, substantially as described.

8. The combination of the retractor B^2 , the 15 extractor C^2 , and the lock-bar E , provided with the recess B^3 , substantially as and for the purpose herein described.

EDWARD G. PARKHURST.
